UNITED STATES PATENT OFFICE.

ROBERT A. HADFIELD, OF SHEFFIELD, ENGLAND.

ARMOR-PIERCING PROJECTILE.

SPECIFICATION forming part of Letters Patent No. 720,242, dated February 10, 1903.

Application filed November 20, 1898. Serial No. 697,579. (No model.)

To all whom it may concern:

Be it known that I, ROBERT A. HADFIELD, a subject of the Queen of Great Britain, residing at Sheffield, county of York, England, 5 have invented an Improvement in Armor-Piercing Projectiles, of which the following description, in connection with the accompanying drawings, is a specification, like letters on the drawings representing like parts.

10 In order to increase the efficiency and penetrative effect against metal plates, it has been common heretofore to apply caps to the end or head of projectiles, and various means have been devised for fastening the cap upon the projectile. In one of the methods of fastening the cap to the projectile it has been proposed to groove or nick the head of the projectile and then apply the cap, which is of softer metal and is forced or pressed onto the 15 head of the projectile and partially into the groove or nick. This method of connecting the cap to the projectile is highly objectionable, for the reason that the groove or nick in the projectile considerably weakens the projectile in that portion where the shock or impact is first felt, resulting in a disintegration and breaking up of the projectile in many cases. In forming the nick or groove in the projectile in this old method of connecting 20 the cap to the head of the projectile the tough outer skin of the projectile is often destroyed, and in any event the groove or nick presents a line or point of weakness in the very part of the projectile which should be strongest. 25 My present invention has for its object the production of a projectile not only free from the stated objections, but of such construction that the projectile is strengthened at its head or near its point by the means provided 30 for securing the cap in place, all as will hereinafter more fully appear.

Figure 1 is a perspective view of a projectile and its cap detached, showing one mode of attaching the cap. Fig. 2, in side elevation, shows the capped projectile. Fig. 3 represents in elevation a projectile with a different form of cap-attaching means, the cap being shown in section; and Fig. 4 is a similar view of yet another form of my invention.

35 In carrying out my invention I cast or forge in the rough a projectile which in its general shape may be of well-known or desired form,

as at P, Figs. 1 and 2, and in finishing the ogival or head portion P', I form on the exterior a retaining rib, bead, or lug, over which 55 the cap C is subsequently pressed in any suitable manner—as, for instance, by hydraulic pressure. This retaining-rib may be made in various forms, as herein shown. In Fig. 1 the retaining-rib b extends around the head 60 portion in a plane at right angles to the longitudinal axis of the projectile and is made more abrupt or shouldered at its rear side at b' than at its front side to facilitate setting the cap and also resist its accidental removal. 65 To resist any tendency of the cap to turn, I remove or slightly recess the rib transversely thereto at one or more points, as at b², to thus present depressions in or through the rib to be entered by a part of the metal of the cap 70 to form a lock therefor against rotation. As will be understood, the cap is preferably of softer metal than the projectile, and when it is applied to the latter it is compressed behind the rib, as at c, Fig. 2, to firmly and securely retain projectile and cap together as one.

It may be desirable in some instances to provide the projectile with more than one retaining-rib, and in Fig. 4 I have shown the 80 head portion P³ of the projectile as provided with two ribs b³ b⁴, arranged in parallelism, and the cap C³ when pressed into place will embrace both ribs.

I have shown in Fig. 3 yet another arrangement of retaining-rib, the projectile-head P⁵ being provided with a spirally-arranged rib b⁵, making one or more turns around the head. With this form of retaining-rib it is not absolutely necessary to attach the cap C⁵ in the 90 first instance, for the correspondingly and interiorly grooved cap could be screwed on as occasion might require, and the projectile could be fired with or without the cap, as deemed most desirable. For instance, in attacking soft armor the cap would probably be unnecessary or even objectionable, while, on the other hand, the cap could be quickly 95 screwed on if hard-faced armor were being attacked. It is to be observed that the rib will be so made that the cap is preferably screwed into place in the direction opposite to the axial rotation imparted to the projectile by the rifling of the gun. If desirable, a small

hole might be drilled in the cap at the end of the spiral of largest diameter to receive a pin 5, riveted in place, which would form a lock to prevent unscrewing of the cap. While the spiral rib may be made sharper, it should preferably be made coarse and of sufficient cross-section to present a firm retaining portion for the cap.

In cast projectiles the rib might be formed to in the casting; but I prefer to machine it in order to secure a truer fit in the cap-groove.

The caps may be of any desired or suitable form and material.

From the foregoing description it will be obvious that by my invention I not only obviate the formation by cutting or otherwise of annular grooves in the projectile, but I actually strengthen the same where it is most necessary and desirable.

20 When spirally-ribbed projectiles are to be delivered already capped, I prefer to subject the cap to pressure after it is screwed into place to thereby securely lock it against removal.

25 Having described my invention, what I claim as new, and desire to secure by Letters Patent, is—

1. A projectile having its head portion provided with an integrally-formed rib or projection, a cap adapted to engage and be retained in place on the head by said rib or projection and means for locking the cap from rotative movement relative to the projectile.

2. An armor-piercing projectile having a 35 hardened head provided with an integral ex-

ternal and also hardened retaining-rib, and a relatively soft malleable cap adapted to engage and be retained in place on the head by pressure externally applied to the cap below or back of the rib.

40

3. A projectile having an external annular retaining-rib extended around the head portion thereof, and an interiorly-grooved cap adapted to fit over the head and be compressed behind the rib, the latter entering the 45 groove in the cap, and means to prevent rotation of the cap on the head.

4. An armor-piercing projectile having an annular rib on the head portion thereof, a cap adapted to engage and be retained in place on 50 the projectile by said rib, and a locking-recess in and transverse to the rib, to prevent rotation of the cap.

5. An armor-piercing projectile having a spiral rib on its head portion and extended 55 from near the point thereof rearwardly, and a correspondingly interiorly grooved cap adapted to be screwed upon the projectile and retained thereupon by co-operation of the rib and groove, the inner surface of the cap 60 fitting snugly upon the external surface of the head portion of the projectile.

In testimony whereof I have signed my name to this specification in the presence of two subscribing witnesses.

R. A. HADFIELD.
